M. KOZLOWSKI

KNIFE GUARD

Filed April 29, 1922

Patented Nov. 20, 1923.

1,474,722

UNITED STATES PATENT OFFICE.

MARTIN KOZLOWSKI, OF MASON TOWN, PENNSYLVANIA.

KNIFE GUARD.

Application filed April 29, 1922. Serial No. 557,267.

To all whom it may concern:

Be it known that I, MARTIN KOZLOWSKI, a citizen of Poland, residing at Mason Town, in the county of Fayette and State of Pennsylvania, have invented certain new and useful Improvements in Knife Guards, of which the following is a specification.

This invention relates to cutlery and has particular reference to a device for paring and slicing fruit and vegetables.

An object of the invention is to provide an improved form of guard with means for removably attaching the same to the blade of a knife whereby the latter is effectively guarded for gaging the depth of cut in paring or slicing.

Another object of the invention is to generally improve and simplify devices of this character so that the same may be manufactured cheaply and in great quantities by stamping operations from sheet material, thus insuring a practical device which may be presented to the public at a low cost and which will be capable of being put into use with the requirement of a minimum amount of skill.

With these general objects in view and others that will appear as the nature of the invention is better understood, the same consists in the novel construction, combination and arrangement of parts hereinafter more fully described, illustrated in the accompanying drawings and pointed out in the appended claims.

35 In the drawings:

Figure 1 is a side elevation of a knife equipped with an improved form of guard constructed in accordance with the present invention.

40 Figure 2 is a transverse sectional view taken upon line II—II of Figure 1.

Figure 3 is a view similar to Figure 2 taken upon line III—III of Figure 1 and showing the knife in reversed position for 45 paring, by dotted lines.

Figure 4 is a longitudinal sectional view upon IV—IV of Figure 1.

Figure 5 is a plan view of the blank from which the guard shown in Figure 1, is 50 formed,

Figure 6 is a plan view of a guard having a modified form of attaching means.

Figure 7 is an edge or end elevational view of the device shown in Figure 6.

55 Figure 8 is a view similar to Figure 6 showing a further modification of the guard.

Figure 9 is a view similar to Figure 7 of the device shown in Figure 8.

Figure 10 is a plan view showing a further modification of the invention adapted 60 for use upon a double edge knife blade.

Figure 11 is an end elevational view of the device shown in Figure 10.

Figure 12 is a view of another modification similar to that shown in Figure 10 with 65 one of the gage elements omitted and adapted for employment for slicing alone and upon a single edge knife blade.

Figure 13 is an end elevational view of the device shown in Figure 12. 70

Figure 14 is a top plan view of still another modified form of the invention adapted for attachment upon a single edge knife blade for use either by right or left handed persons or for slicing or paring, 75

Figure 15 is an end elevational view of the device shown in Fig. 14,

Figure 16 is a view similar to Figure 12 of a device adapted for substantially the same use as the device shown in Figure 12 80 with simplified and modified form of attaching means.

Figure 17 is an end elevational view of the device shown in Figure 16.

Figure 18 is a plan view of still another 85 modification of the invention of the single edge type.

Figure 19 is an end elevational view of the device shown in Figure 18.

Figure 20 is another modification in plan 90 somewhat similar to the device shown in Figure 8 but of the single edge type.

Figure 21 is an end elevational view of the device shown in Figure 20.

Figure 22 is a plan view of another modification involving a single guard strip with separate attached securing tongues for employment either in slicing or paring, 95

Figure 23 is an end elevational view of the device shown in Figure 22, and 100

Figure 24 is a front elevational view of the device shown in Figure 23.

The form of the invention shown in Figures 1 to 5 inclusive is adapted to be employed with a paring knife of the usual form including a blade 5 provided with a handle 6 and having one of its longitudinal edges sharpened to provide a cutting edge 7. The guard for the blade in this form comprises a rectangular blade stamped from sheet metal and provided with a central opening 110 of substantially rectangular form so that

a frame is left consisting of end members 9 and 10 and side or longitudinal gage or guard members 11 and 12. The end members 9 and 10 are provided with extensions 13, and projecting laterally from each extension is a relatively short tongue 14 which projects beyond the side member 12, and a longer tongue 15 which projects beyond the side member 11, these tongues 14 and 15 being formed by slitting the blade, from which the guard is formed, as at 16 and 17, with the slit 17 longer than the slit 16. The side members 11 and 12 are bent laterally in opposite directions as clearly shown in Figures 2 and 3, and to assist in this bending, corner slits are provided as at 18. The tongues 14 and 15 are folded backwardly or return-bent in opposite directions so as to provide spring clips for gripping reception of the blade 5 whereby the guard is held in place upon the blade, the tongues 15 being arranged at one side of the same so as to receive the blade and hold the latter a sufficient distance from the inner edge of the side member 11 as to then adapt the device for slicing, while the tongues 14 are disposed at the opposite side of same for the reception of the knife blade whereby the cutting edge of the latter is held closer to the inner edge of the side member 12 whereby the device is adapted for paring. Thus, when the device is desired to be used for the slicing of vegetables or the like, a knife blade 5 is clipped under the spring tongue 15 as shown by full lines in Figure 3, whereby the edge of the blade is held a sufficient distance from the side frame member or bar 11 for this purpose. On the other hand, if a thin paring is to be removed, the blade 40 may be reversibly positioned beneath the clips or spring tongues 14 as indicated by dotted lines in Figure 3 in which position the edge of the blade is located closer to the bar 12. It will be understood that the cutting edge of the blade comes in contact with the fold of the clips 14 and 15 and thus gage the distance at which said edge is placed relative to the adjacent edge of the operative side guard member or bar. 45

In the form of the invention illustrated in Figures 6 and 7, the device embodies the same elements designated by the same reference characters, the difference being that the clips 14 and 15 are bent inwardly between their ends as at 19 so that the free end portions of the same are directed outwardly as at 20 for permitting the knife blade to be more readily inserted under said clips, and the side members 9 and 10 are bent to dispose the guard members 11 and 12 in oblique position instead of bending the guard members themselves as described with respect to the form of invention shown in Figure 1. This is clearly shown by the end elevational view of Figure 7.

The construction in Figures 8 and 9 is substantially with the construction shown in Figures 6 and 7 except that the guard members are reversely bent relative to the direction of bending of the same in Figure 7 so that the device may be conveniently employed by a left handed person. 70

In the construction shown in Figures 1, 6 and 8, the members 11 and 12 are directed laterally in opposite direction so that the clips 14 and 15 are disposed at opposite sides of the members 9 and 10, but as shown in Figure 10, the guard members 11 and 12 may be directed laterally in the same direction so that the clips 14 and 15 may be bent 80 in the same direction with respect to each other or in the opposite direction to the bending of the members 11 and 12, thus enabling the knife blade to lie at the same side of the device when cooperating with either one of the guard members 11 and 12. The only difference is that the clips 14 and 15 will be of lesser length and folded at a point nearer to the guard members 11 and 12. The knife blade will simply be reversed 90 from one side to the other for cooperating with the desired one of the guard members 11 and 12 as will be apparent.

The construction shown in Figures 12 and 13 is substantially identical with that shown in Figures 10 and 11 with the guard member omitted so that, in this form, the device is adapted for only one operation, either paring or slicing, depending upon the distance at which the knife edge is spaced from the guard member 11 when said knife has its blade cooperatively arranged with respect to the clips 14 and 15. Obviously, the clips 14 and 15 may be so changed in shape and relationship to the member 11 as to adapt 100 the device for either operation.

In the construction shown in Figures 14 and 15 the clips 14 and 15 are folded in the same direction with the clip 1 formed integral with the blank and the clips 14 riveted 110 to the latter as at 20 so that the device shown in this form will be composed of three pieces. In this form the guard member 11 is disposed as is the case with the form in Figures 6 and 7 while the guard member 12 115 extends straight out.

The form of the invention shown in Figures 16 and 17 is substantially the same as that shown in Figures 12 and 13 except that the clips 14 and 15 are bent laterally and rearwardly in opposite directions from the same edge of the extension 13 and the guard member 11 is directed laterally at an angle instead of straight outwardly as in Figure 13, the extension 13 being preferably made 120 longer so as to dispose the clips 14 and 15 in different transverse planes.

In Figures 18 and 19 the extension 13 is provided with a single cooperating pair of clips 14 disposed at the same side of the 125

frame and integrally connected with the single guard member 12, the extensions 13 being integrally connected by a reinforcing strip portion 21 upon which the blade of the knife may rest for insuring rigidity.

The form of the invention illustrated in Figures 20 and 21 is essentially the same as the device shown in Figures 8 and 9 with the guard member 12 and clips 15 omitted so that the device will be adapted for only one operation, either that of slicing or paring as is predetermined.

In the form of the invention shown in Figures 22 to 24 inclusive the guard member 11 is formed separate from the extensions 13' and clips 14' and 15', and the guard member 11 consists of a straight strip of metal with the clips 14' and 15' and extensions 13' riveted together at their ends to the ends of the guard member 11 as at 22, the extensions 13' lying between the clips 14' and 15' at each end and said clips and extensions extending laterally from the guard 11 in the same direction for clipping of the knife blade there beneath as will be apparent. With this form of the invention inexpensive forms of dies may be employed for stamping of the separate parts and the latter may be quickly and effectively united in an assembling operation.

There has thus been provided simple and efficient forms of devices of the kind described and for the purpose specified, the use and advantages of which will be readily apparent to those skilled in the art from the foregoing description.

While the form of the invention herein shown and described is what is believed to be the preferred embodiment thereof, it is nevertheless to be understood that various forms, modifications and arrangement of parts may be made without departing from the spirit and scope of the invention as claimed.

45. What I claim is:

1. In a paring and slicing knife, a guard comprising a metallic plate having an opening therethrough whereby a guard frame is

formed comprising end and side members, said side members being bent transversely in opposite directions, and means integral with said plate for detachably holding said frame upon the blade of a knife for presenting the edge of the latter toward either one of said side members, said means comprising a pair of clips of said metallic plate, the clips upon one side of said plate being nearer the edge of the blade than the clips upon the opposite side of the plate, said pairs of clips being transversely curved in opposite directions.

2. In a paring and slicing knife, a guard comprising a metallic rectangular frame having side guides and end bars, said side guides being bent to extend at angles to the end bars and end clips at each side of the frame reversely bent at opposite sides of the frame and lying within the extreme diameter thereof for attaching the guard to a knife blade.

3. In a paring and slicing knife, a guard comprising a metallic rectangular frame having side guides and end bars, with at least one of the side guides extending at an angle to the end bars, and end clips at each side of the frame bent inwardly and lying within the extreme diameter of the frame for attaching the guard to a knife blade.

4. In a paring and slicing knife, a guard comprising a metallic rectangular frame having side guides and end bars, with the side guides angularly disposed relative to each other, and end clips at each end of the frame lying within the extreme diameter thereof for attaching the guard to a knife blade.

5. In a paring and slicing knife, a guard comprising a metallic rectangular frame having side guides and end bars, with the side guides respectively bent above and below the end bars, and end clips at each side of the frame reversely bent at opposite sides thereof and lying within the extreme diameter of the frame for attaching the guard to a knife blade.

In testimony whereof I affix my signature.
MARTIN KOZLOWSKI.
